UNITED STATES PATENT OFFICE.

MORRIS ISRAEL, OF NEW YORK, N. Y., ASSIGNOR TO DEL-BERT COMPANY, INC., OF NEW YORK, N. Y., A CORPORATION OF NEW YORK.

DESIGN FOR A TEXTILE FABRIC.

Application filed August 6, 1923. Serial No. 6,950. Term of patent $3\frac{1}{2}$ years.

To all whom it may concern:

Be it known that I, MORRIS ISRAEL, a citizen of the United States, residing at New York, in the county of New York and State of New York, have invented a new, original, and ornamental Design for a Textile Fabric, of which the following is a specification, reference being had to the accompanying drawing, forming part thereof.

The figure is a plan view of a portion of a textile fabric illustrating my new design.

I claim:

The ornamental design for a textile fabric, as shown.

In testimony whereof I have hereunto set my hand and seal in presence of two subscribing witnesses.

MORRIS ISRAEL. [L. S.]
